UNITED STATES PATENT OFFICE.

GEORGE C. MURRAY, OF CHICAGO, ILLINOIS, ASSIGNOR TO KEYOKE RAILWAY EQUIPMENT COMPANY, A CORPORATION OF DELAWARE.

UNCOUPLING DEVICE.

1,230,203.

Specification of Letters Patent. Patented June 19, 1917.

Application filed February 2, 1914. Serial No. 815,988.

To all whom it may concern:

Be it known that I, GEORGE C. MURRAY, a citizen of the United States, residing at Chicago, in the county of Cook and State of Illinois, have invented certain new and useful Improvements in Uncoupling Devices, of which the following is a specification.

This invention relates to improvements in uncoupling devices and has for its object to provide an improved form of uncoupler which may be readily attached to and detached from a car, which while providing an efficient form of mechanism will not be affected by the necessary movements of the draw-bar and the coupler mechanism.

Still another object is to provide an uncoupler which may be quickly and easily detached from the car in the event that repairs or replacements become necessary in the mechanism.

These and other objects will be set forth and shown in the following specification and accompanying drawing, in which—

Figure 1 is a perspective portion of the end of a car showing my mechanism applied thereto.

Fig. 2 is a perspective of a detail of the mounting of my uncoupler.

Fig. 3 is a similar view of another detail.

Fig. 4 is a section taken through a portion of the mounting of the uncoupler.

Fig. 5 is a perspective detail view of a slight modification.

Like numerals refer to like elements throughout the drawing, in which 10 designates generally the usual form of coupling mechanism having the coupler-pin 11 slidably mounted therein, this coupler-pin being

provided with a loop or eye 11^a. What I term uncoupler rod 12 has angularly disposed arms 12^a, 12^b. The arm 12^a is of sufficient size to extend through the eye 11^a of the coupler-pin and it loosely fits therein and permits sliding of the coupler 11 therewith, as will be obvious. The extremity of the other arm 12^b is looped to form an eye 12^c, as clearly shown in Fig. 1.

An operating rod 13 is provided with the downwardly extending handle portion 13^a and is rotatably mounted or journaled in the bearing members 14, 15, respectively. The bearing member 14 comprises a bracket or casting centrally apertured at 14^a and is

secured to the end sill of the car by bolts, 55 rivets, or the like, 14^b.

The supporting member 15 comprises a member 15^a, which I term a seat member, and the locking member 15^b, see Figs. 2 and 3. The former comprises a plate 15^c apertured at 15^d for fastening to the end sill of the car. A seat or chair 15^e is carried by the plate 15^c and is concaved, as indicated by the numeral 15^f, to furnish a journal bearing for the rod 13. At its upper portion 65 the plate 15^c is provided with the curved flanges 15^g spaced apart as shown in Fig. 2. At its lower portion the plate 15^c has lugs 15^h apertured at 15ⁱ. The locking member 15^b is provided with the pintle 15^k in 70 which extends downwardly the U-shaped loop 15^l, the same being bent directly downwardly from the pintle 15^k and then looped as shown in Fig. 3. Carried by the loop 15^l are the spaced apart outwardly extending lugs 15^m.

When the device is assembled the pintle 15^k is carried between the end sill and the flanges 15^g, the latter furnishing a rotatable mounting for the same, and the loop 15^l 80 fits around and coacts with the seat 15^e to maintain the rod 13 in rotatable position. The lugs 15^m fit between the lugs 15^h, the apertures in both sets of lugs alining when in locking position, in which position a, 85 cotter-pin 16 may be passed therethrough and spread at its end, as shown in Fig. 1. Adjacent the locking member 15^b the rod 13 is offset, as indicated by numeral 13^b, for a purpose to be hereinafter described. 90

The eye 12^c of the uncoupling rod 12 is loosely mounted on the offset portion 13^b of the rod 13 and extends outwardly therefrom substantially at right angles in the form shown in the drawings, the length of 95 the arm 12^b being determined by the position of the coupler-pin 11 with reference to the position of the operating rod 13. The rod 13 has the portion 13^a bent at right-angles to the offset portion 13^b and a portion 13^a thereof is reversely bent substantially at right-angles to portion 13^a extending under the arm 12^b of rod 12. At its extremity the portion 13^a is upturned slightly, as indicated at numeral 13^c. 100

When the device is in assembled position, as shown in Fig. 1, it is apparent that the coupler-pin may be raised to "lock set" po-

sition by raising the handle portion 13^a of rod 13 whereupon the reversely bent portion 13^a of the rod will coat with arm 12^b of coupler rod 12, the same being in effect fulcrumed at its eye 12^c so that the said movement of the rod 13 will raise the coupler-pin 11^a to its lock set position, in which an ordinary coupling construction will be retained until the cars are again coupled. One advantage of my construction is that the operating rod may drop to position shown in Fig. 1, while the coupler is in lock set position, the rod 12 being maintained in its upper position by the coupler-pin. Inasmuch as regulations and requirements demand that uncoupling mechanism permit in and out movement of the draw-bar mechanism and lateral movement thereof, I have provided for such movements by making the rod 12^a of such diameter as to fit loosely in the eye 11^a of the coupler-pin, thereby providing for a certain amount of relative sliding movement of the latter with respect to the rod 12. At the same time the loose mounting of the eye 12^c upon portion 13^b of the rod 13 provides for a certain amount of pivotal movement of the rod 12 laterally relative to the rod 13, as will be apparent. The upturned portion 13^a will prevent movement of the rod 12 out of operative position with respect to the operating rod 13, as will be apparent.

In use it is very often the case that the uncoupling rods become bent or twisted or for other reasons require replacement, and to render such repair and replacement easy of accomplishment, I have provided the locking means 15 described above. When it is desired to remove the coupler mechanism it is merely necessary to remove the cotter-pin 16, raise the locking member 15^b and slide the rod 13 bodily to one side until the rod 12 is removed from engagement with the coupler-pin 11^a, when said rod may be partially rotated and removed around the portions 13^c, 13^d and 13^e of the rod 13. If it is desired to remove the rod 13 also the same may be swung outwardly to permit the operating handle 13^a to be drawn through the aperture 14^a of member 14, the said aperture being enlarged at each end, as shown in

Fig. 4, to expedite such withdrawing. When in assembled position the rod 13 is prevented from accidental removal and too great a lateral movement by the offset therein, which will contact with the locking member 15 to limit such movement.

It will be apparent that I have provided mechanism which will operate efficiently in uncoupling the car and one which is not only inexpensive to manufacture, but which may be readily attached to and detached from a car, this feature enabling repair on the mechanism without removing the car from active service, which is a great advantage.

In Fig. 5 I have shown a modification in which the end 13^e of rod 13' is extended upwardly above and then rearwardly over the arm 12^b being then bent downwardly at its end to terminate adjacent the portion 13^c of rod 13'. This will permit, as is obvious, sufficient up and down movement of arm 12^b with similar movement of the draw-bar, and will also prevent accidental removal of the rod 12 from rod 13', this construction serving also to limit sliding of rod 12 on rod 13'.

It will be apparent that my device is susceptible of many changes and modifications, and I do not wish to be restricted to the form shown and described beyond the scope of the appended claim.

What I claim is:

An uncoupling mechanism comprising an operating rod rotatably mounted on a car, said operating rod being provided with an offset portion and a reversely bent portion spaced therefrom, and an uncoupling rod adapted to engage the coupler-pin to said car, said uncoupling rod being fulcrumed on said offset portion of said operating rod, said reversely bent portion of said operating rod being arranged to contact with and operate said uncoupling rod upon proper movement of said operating rod.

In testimony whereof, I have subscribed my name.

GEORGE C. MURRAY.
